UNITED STATES PATENT OFFICE.

JOHN ALBERTOLI, OF SAN FRANCISCO, CALIFORNIA.

APPARATUS FOR MARKING CANS.

Application filed March 25, 1922. Serial No. 546,841.

To all whom it may concern:

Be it known that I, JOHN ALBERTOLI, a citizen of the United States, residing at San Francisco, in the county of San Francisco and State of California, have invented new and useful Improvements in Apparatus for Marking Cans, of which the following is a specification.

This invention relates to improvements in apparatus for marking empty cans preliminary to canning operations and has particular reference to a simply constructed and inexpensive apparatus by means of which cans may be marked so as to distinguish grades of material placed within the cans and to designate the packer.

An object of the invention is to provide marking apparatus for cans which may be readily and easily operated, at will, to mark either one of a plurality of brand marks upon the cans, thus making possible the use of but one machine for applying different marks to the cans and eliminating the necessity of changing or resetting the machinery each time one of the different marks is to be applied to the cans.

Another object of the invention is to provide marking apparatus of the character described which may be readily incorporated with the devices for delivering empty cans to canning tables, the device of the invention being so arranged as to intercept the cans as they are conveyed to the canning tables and includes a hand operated means readily accessible to an operator at the canning table, the hand operated means being so arranged that when moved in one direction will provide for the marking of a certain grade mark on the cans and when turned in another direction will make another grade mark upon the cans.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings: 55

Fig. 1 represents a top plan view of the marking device of my invention.

Fig. 2 represents a side elevation of the marking device.

Fig. 3 represents a front elevation of the marking apparatus operatively associated with the can feeding and delivering means.

Fig. 4 is a top plan view with certain parts removed showing the feeding and delivering means of the apparatus also the canning table.

Fig. 5 is an end view of a can showing one of the grade marks thereon.

Fig. 6 is a side view of a can with a special mark thereon. 70

Fig. 7 is an end view showing the can with another mark thereon.

Essentially the invention comprises a hand operated member which receives cans from a gravity feed chute and may be moved in one direction to cause a certain mark to be made upon the cans, and in another direction to cause another mark to be made upon the cans, in either instance, after the marking of the can, the movable device causes the can to drop into a delivery chute, there being one for cans of one mark and another for cans having another mark. The apparatus of the invention is placed adjacent to canning tables so that the operator may in receiving the cans preliminary to filling them, or otherwise carrying out some step in the canning operation, cause the cans to be given either one of several grade identifying marks with but a simple operation and also cause the cans to be delivered in separate chutes or delivering devices so as to be readily accessible to the operator after having been marked. 80

Referring to the embodiment of the invention shown in the accompanying drawings, the apparatus of my invention is mounted upon or adjacent to a canning table upon a support 1, preferably so as to be disposed above the table, and comprises a base 2, extending upwardly from which is a shaft 3, which latter supports a movable, preferably rotatable and circular table 4. The table 4 is provided with a plurality of radially extending pockets 5, which are open on the upper and lower sides and at their outer ends, said pockets being of such sufficient size to accommodate an empty-can. 95

An empty can conveyor or feed chute 6 leading from a source of supply of empty cans, has an upright delivery portion disposed over the table 4 so that the cans will gravitate from the conveyor into the pockets 5 of the table, one at a time. As the table is turned away from the delivery end of the conveyor 6, the next uppermost can engages with the table portions 7 which lie between the pockets 5 and is thereby held against discharging from the conveyor.

Immediately beneath the table 4 and discharge end of the conveyor 6 is a comparatively narrow support or shelf 8 upon which the lower sides of the cans engage when mounted in the pockets 5. This support or shelf is of such size that when the table 4 is turned, say, for example, thru a part of one revolution, the cans will disengage from the support and be free to gravitate or roll into discharge conveyors 9 and 10. The conveyors 9 and 10 are located on opposite sides of the shelf or support and commence in slightly forwardly and downwardly inclined portions 11, then drop in abruptly inclined portions 12 and terminate at their other ends in upturned discharge ends 13 located adjacent to the canning table, not shown.

30 I provide means for automatically marking the cans when the table 4 is turned with a can mounted in one of the pockets 5 thereon, there preferably being two marking devices 14 and 15 so that when the table is turned in one direction the can will be given a certain mark and when in the other direction a different mark. The devices 14 and 15 are mounted upon the support 2 close to the table 4 and upon opposite sides of the discharge end of the conveyor 6. The marking devices are identical as to construction except as to the stamps, and each of them comprises a body portion 16 fixed to a shaft 17 journaled in bearings 18 mounted on the support 2. The body portion 16 carries a marking stamp 19 having the desired type or dies thereon, to imprint a grade mark as shown at 20 Fig. 5 upon the ends of the cans also the packer's or canner's number mark as shown at 21. The stamp 19 is provided with a stem 22 slidable horizontally thru spaced apertured projections 23 extending upwardly from the body portion 16. The stem 22 is provided with an abutment 24 adapted to engage the outer end of an expansion spring 25 which surrounds the stem. By this arrangement the stamp 19 yields when engaged with a can so as to properly apply the imprint to the can. The stamp 19 is so positioned that when the table 4 is moved in either direction with a can engaged in one of the pockets 5, the closed end of the can will contact with and press inwardly the stamp 19.

The stamping device as a whole, is moved 65 in the same direction as the table and can. As a means for turning the devices 14 and 15, gears 27 are fixed to the lower sides of the body portions 16 and to the shafts 17. These gears are secured to the body portions 70 by screws 28 extending thru slots 29 in the body portions and into the gears, whereby the gears may be adjusted relative to the body portion to vary the operation of the devices. The gears 27 mesh with a large 75 gear 30 journaled upon a short shaft 31 on the support 2, the said gears 27 being disposed on opposite sides of the gear 30. The gear 30 meshes with a similar gear 32 mounted upon an upright shaft 33 journaled 80 on the support 2. Above the gear 32 is a smaller gear 34 which meshes with a drive gear 35 fixed to the shaft 3 and lower side of the table 4. Thus, it will be seen that when the table 4 is turned in either direction, 85 the stamps 19 on the devices 14 and 15 will be turned towards the periphery of the table so as to engage the ends of the cans in the pockets 5.

Suitable inking devices may be provided 90 for the stamps 19 of the devices 14 and 15. As shown, two inking devices designated 36 and 37 are provided, one for each of the marking devices. Each of these inking devices comprises a frame 38 pivoted as at 95 39 near one end to the support 2. Mounted in the frame 39 is an ink applying roller 40 with which the stamp 19 is adapted to engage so as to be inked. The inking roller 40 engages with a perforated magazine or 100 ink roller 41 journaled in the frame 38. The ink is transferred to the applying roller 40 by the magazine roller 41 and from thence to the particular stamp 19 once during each revolution of the stamping device. 105 To provide for movement of the applying roller into position so as to contact with the stamp 19, each frame, near its outer end is provided with an elongated clamp 42 comprising arms 43 adapted to frictionally engage on opposite sides of the gear 30, said arms being secured at their inner ends as at 44 to the frame 38. These arms are pressed together by a spring device 45, so that they will have frictional contact with 115 opposite sides of the gear 30. The arms for the clamps of the two inking devices are disposed on opposite sides of the gear so that when the gear 30 is rotated in one direction, say, from left to right, the arms 120 43, the clamp 42 and the frame 38 of the device 37 will be moved from the dotted line position shown in Fig. 1, to the full line position and thereby cause the applying roller 40 to engage and apply ink to 125 the stamp 19. As a means for regulating the movement of the frame 38 of each of the inking devices, there are provided ad-

justable stops 47 and 48 mounted on the support 8. Between these stops a rigid projection 49 of the frame extends.

To provide for keeping tally on the number of cans marked, a suitable marking device 50 is mounted above the discharge end of the conveyor 6, so that it will tally each can as it passes beyond said device. A similar device 51 is mounted at the intake end of the discharge conveyor 9. These devices may be of any suitable construction well known in the art, and are actuated by trip members 52 extending into the paths of the cans as they are advanced in the respective conveyors.

Since the cans are marked upon the ends, in order to provide for readily distinguishing cans bearing one mark from cans bearing another mark, the cans bearing one of the marks are caused to be marked with a ring, or part of a ring, on the main bodies thereof, as shown at 53 in Fig. 6. Preferably the chute or conveyor 9 is provided with a marking device 54 adapted to mark the mark 53 upon the cans. This device 54 comprises an inked wick or a strip of absorbent material 55 held in the frame 56 which extends along the lower side of the portion 11 of the conveyor 9. Thus as the cans roll onto the conveyor 9 they are given a ring-like black mark on the cylindrical walls as shown at 53 in Fig. 6.

It is now the custom in canneries to apply grade marks to the empty cans preliminary to the canning operation. With the apparatus of my invention installed adjacent to a canning table, as the cans are delivered thru the conveyor 6, the operator may cause the cans to be marked with a grade designating mark, by turning the table 4, preferably by hand. When it is desired to mark the can with the first or highest grade mark, for example, the one shown in Fig. 5, the operator will turn the table 4 from left to right. When a pocket 5 is brought opposite the discharge end of the conveyor 6 the lowermost can in the conveyor will drop into the pocket and as the table is turned to the right, the next uppermost can will rest upon the portion 7 of the table which lies between the pockets 5. The can within the pocket 5 is moved to the right with the table and as the table is thus moved, the train of gears causes the marking device 14 to rotate so as to bring the stamp 19 into engagement with the outer closed end of the can designated A, in Fig. 2. Continued rotation to the right causes the stamp 19 to move free of the can and the can to move free of engagement with the support 8, the movements of the table and marking device 14 being indicated by the arrows in Fig. 1. As soon as the can disengages from the support 8, it rolls onto the slightly inclined portion 11 of the con-

veyor 9 and then gravitates in the conveyor 9 to the lower upturned end 13 thereof, where it may be removed from or allowed to stand in, said conveyor. By continuing the left to right movement of the table, the operator may continuously cause cans to be removed from the discharge end of the conveyor 6 and to be marked by the device 14, then delivered into the discharge chute 9. This operation of turning the table 4 may be effected with one hand of the operator. As the cans after having been marked with designations shown at 20 and 21, in Fig. 5, roll into the portion 11 of the conveyor 9 they contact with the inking device 54 and are given a ring-like mark on their circular walls which readily distinguish the cans for containing high grade products from the cans marked to receive the next best or lower grade.

Should the operator desire to apply a second grade mark to the ends of the cans, the table is turned from right to left or in the opposite direction so that the cans are moved into position to be marked by the marking device 15 and are then moved off of the opposite side of the support 8 into the discharge conveyor 10. It will thus be seen that the marking operation may be continuously carried out by turning the table 4 in either direction. When the table is turned continuously in either direction, the inking device for the stamping device being operated will be brought into position from time to time to apply ink to the stamp 19. The difference of the sums shown by the registering or counting devices 50 and 51, will indicate the number of cans marked, in this instance, with the low grade mark, as shown at 20 in Fig. 5.

With the apparatus of my invention it will be seen that the application of different marks to cans may be readily and easily effected by a canning operator at the time of the delivery of the cans to the operator for canning operations. In this way a great deal of time, labor and operation expense may be saved particularly since the marking operation may be continuously carried out to apply one or more marks, as desired, also the packer's number and cause the differently marked cans to be segregated and if desired stacked within the discharge conveyor.

While I have shown a particular form of revolvable table which is hand operated, I wish it understood that I may use any kind of moving device which will serve the purpose of moving cans from the feed conveyor so as to cause marking thereof and then distributing differently marked cans into different discharge conveyors.

I claim:

1. Apparatus for marking cans comprising in combination with means for conveying cans from a source of supply of cans to

- stations in a cannery at which stations the cans are to be filled, marking devices for applying differing marks to cans and means for moving the cans into position to be marked by either of the marking devices without arresting the advancement of the cans by said conveying means.
2. Apparatus for marking cans comprising means for conveying cans from a source of supply of cans to stations in a cannery at which points the cans are to be handled, marking devices for applying different marks to cans and means selectively operable to cause the cans to be moved into position to be marked by either of said marking devices during the progress of said cans and means for making an additional mark on cans bearing one of said differing marks during movement thereof by said conveying means.
3. Can marking apparatus comprising devices for making different marks upon cans, means for supporting a can and moving it into engagement with either of the devices and means operating upon movement of the last named means for actuating the marking devices.
4. A can marking device comprising a revolving table having a plurality of can receiving pockets thereon, a can feeding apparatus arranged to discharge cans into pockets of the table as the pockets are brought opposite the feeding apparatus and means which when the table is rotated in different directions, will apply different marks on the cans.
5. A can marking device comprising a revolving table having a plurality of can receiving pockets thereon, a can feeding apparatus arranged to discharge cans into pockets of the table as the pockets are brought opposite the feeding apparatus, means which when the table is rotated in different directions, will apply different marks on the cans and delivery chutes into which the cans are moved after having been marked.
6. Can marking apparatus comprising in combination with means for feeding empty cans, a revolvable table having a plurality of can receiving pockets, each of which pocket is adapted to receive a can when moved opposite the feeding means and means which when the table is rotated continuously in either direction will apply marks upon the cans mounted in said pocket.
7. Can marking apparatus comprising in combination with means for feeding empty cans, a revolvable table having a plurality of can receiving pockets, each of which pocket is adapted to receive a can when moved opposite the feeding means and means which when the table is rotated in one direction will cause a mark to be made upon a can held in a pocket and when ro-

tated in the other direction will cause a different mark to be made upon a like can held in a pocket of the table.

8. Can marking apparatus comprising a movable member arranged to move cans, and marking devices which when the said member is moved in one direction will make a mark upon cans moved by said member and when moved in another direction will make a different mark on cans.

9. Can marking apparatus comprising a movable member arranged to move cans, and marking devices which when the said member is moved continuously in one direction will make a mark upon cans moved by said member and when moved continuously in another direction will make a different mark on cans.

10. Can marking apparatus comprising a support over which cans are movable, means for moving the cans over the support in a plurality of directions and means which when the cans are moved in one direction will make a mark on the cans and when the cans are moved in another direction will make a different mark on the cans.

11. Can marking apparatus comprising a support over which cans are movable, means for moving the cans over and off of the support in a plurality of directions and means which when the cans are moved in one direction will make a mark on the cans and when the cans are moved in another direction will make a different mark on the cans.

12. Can marking apparatus comprising a support over which cans are movable, means for moving the cans over and off of the support in a plurality of directions, means which when the cans are moved in one direction will make a mark on the cans and when the cans are moved in another direction will make a different mark on the cans and delivery members onto which the cans are moved from the support.

13. Apparatus for marking cans comprising a can feed chute, a plurality of delivery chutes into which cans from the feed chute are delivered and means for intercepting cans between the feed and delivery chutes marking them with different marks.

14. Can marking apparatus comprising a movable member arranged to move cans and marking devices which when the said member is moved in one direction will make a mark upon cans moved by said member and when moved in another direction will make a different mark on cans, delivery devices into which differently marked cans are directed and marking means associated with one of the delivery devices for marking conspicuously upon the cans delivered into said device a distinguishing mark.

15. Can marking apparatus comprising a can feed chute, a plurality of delivery chutes into which cans are directed from

the feed chute and which are arranged to deliver differently marked cans to the working station of the packer or canner and means operatively associated with the delivery chutes for marking different marks on the cans.

16. The method of marking empty cans preliminary to packing or filling of the cans which consists in feeding empty cans towards the working station of a packer or canner, selectively marking different marks upon cans during the progress thereof and separately delivering the differently marked cans to points within reach of the canner or

15 packer.

17. The method of marking empty cans preliminary to packing or filling of the cans

which consists in feeding empty cans towards the working station of a packer or canner, selectively marking different marks 20 upon cans and separately delivering the differently marked cans to points within reach of the canner or packer.

18. Can marking apparatus comprising means for moving cans from a source of supply of cans to a working station of a cannery or packer, means for causing cans during the progress thereof to be directed in different paths while being advanced and marking means which when the cans are 30 directed in one of the different paths will make a mark on the cans.

JOHN ALBERTOLI.
